DESIGN FOR AN ELECTRIC FIXTURE HANGER PLATE

Carl X. Meyer, St. Louis, Mo., assignor to Day-Brite Lighting, Inc., St. Louis Mo., a corporation of Missouri

Application March 7, 1945, Serial No. 118,308

Term of patent 14 years

(Cl. D48—23)

To all whom it may concern:

Be it known that I, Carl X. Meyer, a citizen of the United States and a resident of the city of St. Louis and State of Missouri, have invented a new, original, and ornamental Design for an Electric Fixture Hanger Plate, of which the following is a specification, reference being had to the accompanying drawing, forming part thereof.

Fig. 1 is a bottom plan view of an electric fixture hanger plate, showing my new design.

Fig. 2 is a top plan view of said hanger plate.

Fig. 3 is a side elevational view of said hanger plate,

Fig. 4 is a central vertical longitudinal sectional view of said hanger plate, on the line 4—4 of Fig. 2.

Fig. 5 is an end elevational view of said hanger plate; and

Figs. 6 and 7 are vertical cross-sectional views on the lines 6—6 and 7—7, respectively, in Fig. 2.

I claim:

The ornamental design for an electric fixture hanger plate, as shown.

CARL X. MEYER.
